UNITED STATES PATENT OFFICE.

MOSES MONROE ABRAMS, OF ADAMS, ALABAMA.

FERTILIZER-DISTRIBUTER AND PLANTER.

SPECIFICATION forming part of Letters Patent No. 639,009, dated December 12, 1899.

Application filed May 26, 1899. Serial No. 718,398. (No model.)

To all whom it may concern:

Be it known that I, MOSES MONROE ABRAMS, a citizen of the United States, residing at Adams, in the county of Chilton and State of Alabama, have invented certain new and useful Improvements in Fertilizer-Distributers and Planters, of which the following is a specification.

The object of my invention is the production of a fertilizer-distributer and planter which shall be simple in construction, cheap in first cost, made up of few parts, which shall be adapted for attachment to the beam of any type of plow, and which, withal, shall constitute a superior device for the purposes intended.

My invention consists, objectively, in a base piece or plate provided with means for detachably securing the same to the beam of a plow, an operating-wheel having an axle upon which is supported a toothed distributing-wheel, a hopper, and an agitator, the said hopper and toothed wheel being adjustable relatively to the base-plate.

It further consists in certain novelties of construction and combination of parts hereinafter set forth and specifically claimed.

The accompanying drawings illustrate one example of the physical embodiment of my invention constructed according to the best mode I have so far devised for the application of the principle.

Figure 1 illustrates a plow with the distributor or planter attached, one side of the hopper being broken away to show the location of the agitator. Fig. 2 is a plan view of Fig. 1 with the hopper removed for the purpose of showing the relative positions of the several elements which are in a plane below the plane of the hopper. Fig. 3 is a perpendicular section of Fig. 1, taken in a line parallel with the axle. Fig. 4 is a detail view of the agitator.

Referring to the several figures, the letter A designates a plow; B, the beam of the plow; C, the moldboard and share, which may be of any desirable type or form; D, the hopper; E, the base-piece, preferably made of metal, though wood may be employed in lieu thereof. F F are U-bolts and nuts which serve to secure the base-piece to the beam of the plow.

G is a hole made in the base-piece.

H H are set-screws consisting of bolts and butterfly-nuts, each bolt being located in a hole made in the base-piece.

I I are bearings placed at the ends of the plate.

J J are bolts which secure the bearings in place.

K is an operating-wheel; L, an axle, square in cross-section, threaded at one end, rigidly secured to the operating-wheel at the other end, and rotating in the bearings I I, which are attached to the under side of the base-piece.

M is a toothed distributing-wheel having a square hole to fit the axle, which it frictionally engages and upon which it is adapted to slide longitudinally.

N is an adjustable plate in frictional contact with the base-piece, as shown.

O O are slots made in the adjustable plate to receive the bolts H H.

P is a slot made in the adjustable plate for the purpose of receiving the toothed distributing-wheel.

Q is an enlarged part of the slot.

R is a feed-regulator pivoted to the adjustable plate.

S is a slot; T, a set-screw consisting of a bolt and butterfly-nut.

U is the hopper, which may be secured to the base-piece in any desirable way.

V is a spring made of metal and constituting an agitator.

W designates the bolts which secure the spring to the hopper.

X is a slot made in the end of the spring, and Z Z are fingers adapted to occupy positions each side of the teeth of the toothed distributing-wheel.

The *modus operandi* of the distributor will be obvious from an inspection of the drawings. When the plow is advanced, the wheel K, being in contact with the earth, causes the axle to revolve and with it the toothed distributing-wheel M. The material within the hopper is agitated by the spring V, which successively engages the teeth and insures a constant and regular delivery through the slot.

The pivoted feed-regulator R can be ad-

justed so as to control the size of the opening at Q. The plate N with the hopper attached may be shifted relative to the plate E through the medium of the bolts H and slots O, the 5 toothed distributing-wheel being also shifted at the same time, inasmuch as it is loose upon the square axle.

From the foregoing description it will be apparent that I have produced a fertilizer-10 distributor and planter which fulfils all the conditions set forth as the object or end of my improvements.

While I have illustrated and described but one example of the physical embodiment of 15 my invention, I do not thereby intend to limit its scope to such example, inasmuch as many changes and modifications may be introduced in its manufacture and equivalents substituted for each of the several elements 20 without constituting a substantial departure. I have shown the distributor proper attached to a plow having a single beam; but it may be used with a plow having a double beam or with a plow having a plurality of shares. 25 What I claim as new, and desire to secure by Letters Patent, is—

1. A fertilizer-distributer and planter, comprising a base-piece; an operating-wheel provided with an axle upon which is supported a 30 toothed distributing-wheel, said axle being journaled in bearings on the base-piece; a hopper; and an agitator located within the hopper and engaging the toothed distributing-wheel; the said distributor proper being 35 provided with means for detachably securing the same to the beam of a plow; in substance as set forth.

2. The combination in a fertilizer-distributer and planter, of a base-piece provided 40 with bearings; an operating-wheel and axle adapted to rotate in the bearings; a toothed wheel on the axle; an adjustable plate to which is secured a hopper; and an agitator

engaging the teeth of the toothed wheel; in substance as set forth.

3. The combination with a fertilizer-distributer and planter, constructed substantially as described, of an axle which is square in cross-section; a toothed wheel adapted to slide longitudinally upon the axle; a plate 50 supporting a hopper adjustable relative to a base-piece; and an agitator engaging the teeth of the distributing-wheel; in substance as set forth.

4. The combination with a fertilizer-distributer and planter, constructed substantially as described, of a base-plate; an adjustable plate, N, provided with a slot which is enlarged at Q; and a feed-regulating device adapted to partially close the slot; in substance as set forth.

5. The combination with a fertilizer-distributer and planter, constructed substantially as described, of a toothed wheel adapted to be rotated by the operating-wheel; and 55 an agitator consisting of a spring, one end of which is secured to the hopper and the other end having a slot and fingers which engage the toothed distributing-wheel; in substance as set forth.

6. The combination in a fertilizer-distributer and planter, of a base-piece, E; an operating-wheel, K; an axle, L, square in cross-section; a distributing-wheel; a plate, N, provided with a slot; a hopper, U, adjustable 75 with the plate, N, relative to the base-piece; an agitator; and means for detachably securing the plate, E, to the beam of a plow; in substance as set forth.

In testimony whereof I affix my signature 80 in presence of two witnesses.

MOSES MONROE ABRAMS.
